To all whom it may concern:

Be it known that I, Tora Coleman, a citizen of Latvia, residing in the city of New York, county of New York, and State of New York, have invented a new, original, and ornamental Design for a Dress, of which the following is a specification, reference being had to the accompanying drawing, forming part thereof.

The characteristic feature of my design resides in the combination on the instant dress of large, fringe trimmed scallops on the front closure, each scallop having two buttons as shown.

I claim:

The ornamental design for a dress substantially as shown and described.

TORA COLEMAN.
